UNITED STATES PATENT OFFICE

ISRAEL PERPER, OF BRONX, NEW YORK

SHADE ROLLER MOUNTING

Application filed April 28, 1930. Serial No. 447,908.

The present invention relates to shade roller mountings and aims to provide certain improvements therein. It is particularly directed to a type of mounting which is secured directly to the window sash so that the shade roller is movable therewith as the sash is lowered or raised in the window frame.

Among the objects of the present invention the following may be enumerated: to provide a device of the type described which can be readily mounted on the upper of a pair of window sashes and which can be quickly removed so that the window sashes can pass one another and access be thereby readily had to the outside of said windows for cleaning the same; one in which the shade roller is instrumental in locking the shade roller supporting brackets in place on the window sash; one which is exceedingly simple in construction, readily mounted in position, efficient in operation and which can be manufactured and sold at a reasonable price.

The foregoing and other objects of the invention are accomplished by the novel mounting means which I have provided, the construction and operation of which will be clearly understood from the detailed description which follows, reference being had to the accompanying drawings, wherein:

Figure 1 is a broken perspective view showing an embodiment of the invention.

Fig. 2 is a section taken substantially along the plane of the line 2—2 of Fig. 1.

Fig. 3 is a section taken substantially along the plane of the line 3—3 of Fig. 1, the bracket member being therein shown in unlatched position.

Fig. 4 is a section taken along the plane of the line 4—4 of Fig. 3.

Fig. 5 is a section taken along the plane of the line 5—5 of Fig. 4, the bracket member being removed and the rails of the sashes A and B being shown as disposed opposite each other.

Referring to the drawings, let A indicate the upper sash and B the lower sash of a pair of window sashes which are vertically slidable in grooves C, C', and D, D', respectively, of a window frame E, the grooves C,

C' being spaced from the grooves D, D' by the vertical ribs e, e'.

Mounted on the inner face of the top rail a of the window sash A in close proximity to the vertical lateral edges of said sash are a pair of socket elements F, F, each of which is preferably formed from flat sheet metal by having its central portion f depressed out of the normal plane of the metal but parallel thereto, thereby leaving the edge portions f' through which pass the securing screws f². The socket in the member F is therefore provided by the central depressed portion f in cooperation with the face of the window sash and as is apparent from the drawings said socket extends in a vertical direction.

For cooperation with socket elements F and adapted to be supported thereby are a pair of complementary angular bracket members G and H, the short arms of which are each formed with a depending tongue g and h, respectively, of less width than the recess in the socket element F, and each of said tongues being provided at its free end with a lateral lip g' and h', respectively, said lips being directed outwardly toward the vertical edges of the sash. The tongues g and h are greater in length than the height of the socket elements F by a distance equal to the height of the tongues g' and h'. At the top of the tongues g and h the bracket arms are formed with overhanging parts g², g³ and h², h³, respectively, which are adapted to seat on the top edges of the portions f' of the socket elements. The long arms of the sockets are provided with depending ends provided with aligned openings g⁴ and h⁴, respectively, for accommodating the end pins of a spring shade roller. As is conventional one of these openings is of circular form and the other of oblong form for accommodating the pins j and j' at the opposite ends of a shade roller J. It will be apparent that if desired the arms G and H may be made to support a plurality of shade rollers by multiplying the openings therein. The brackets G and H are detachably mounted and supported by the socket elements F by having the tongues g and h respectively engaging within the sockets formed by the recesses in the

100

socket elements and the face of the window sash and by having the overhanging parts g^2 , g^3 and h^2 , h^3 resting on the parts f' of the socket elements. When the shade roller J is mounted in the openings g^4 and h^4 the brackets G and H are each laterally moved outwardly toward its respective side of the window sash and when so moved the lips g' and h' are caused to underlie the lower edges 10 of the socket elements and thereby provide latching means for preventing the accidental withdrawal of the bracket members from the socket elements. To accomplish this it will of course be understood that the shade roller 15 J must be of a length to cause such lateral movement of the bracket members. It will also be understood that the bracket members being formed of sheet metal they will possess a certain amount of inherent resiliency which 20 will also serve to effectively support the shade roller and compensate for any deficiency or excessive length of such shade roller.

Should it be desired to clean the windows the shade roller J can be readily removed, 25 whereupon the brackets G and H can be lifted out of their respective socket elements, thereby leaving the upper sash A to freely pass the lower sash B , it being understood that the thickness of the spacing ribs e and 30 e' are greater than the depth of the socket elements F . To again mount the shade roller it is merely necessary to insert the brackets in their respective socket elements and position the pins on the shade roller into the 35 openings provided therefor in said brackets.

While I have shown and described a preferred embodiment of my invention, it is to be understood that I do not wish to be limited to the details of construction disclosed, since 40 modifications thereof may be resorted to without departing from the spirit of the invention.

What I claim is:

1. A shade roller mounting comprising a member adapted to be secured to the face of 45 a window sash and to provide therewith a socket, an angular bracket having an arm adapted to support one end of a shade roller and an arm having a part insertable into the socket and a part adapted to seat against the 50 top of the member, the part which is insertable into the socket being of less width than said socket and adapted for lateral movement therein and cooperating parts on said socket member and said insertable part for 55 latching said members together when said insertable part is laterally moved within the socket member.

2. A shade roller mounting comprising a sheet metal member having a central portion 60 which is offset from the plane of the metal whereby to provide a socket when said member is secured to a window sash or the like, an angular bracket formed of sheet metal, one arm of said bracket having an opening 65 to receive one end of a shade roller, the other

arm of said bracket having a tongue which is provided at its free end with a lateral lip, said tongue being of less width than the socket and engageable therein and adapted to have its free end protrude therethrough 70 and a second part on said arm adapted to seat on the top edge of said socket containing member when the tongue is seated therein, said tongue being laterally movable in said socket to a position where the lateral lip underlies the lower edge of the socket containing member to provide a latch for preventing accidental withdrawal of the bracket from the socket member. 75

3. In combination with a movable window sash having a flat socket member near each lateral edge, of a pair of complementary angular bracket members, each having an arm provided with a tongue engaging vertically in one of the sockets and a part resting on the top edge of said sockets, said tongues being each of less width than the sockets and provided at their free ends with a lip which is directed outwardly toward the window frame, and an arm having an opening, the 80 openings in said arms being in horizontal alignment, and a shade roller supported in said brackets with the end pins of the roller engaging in the openings in said arms, the shade roller when mounted in said brackets 85 causing an outward lateral movement of the tongues, whereby the lips thereon are moved into position to underlie the lower edge of the socket members to latch the brackets 90 against accidental removal. 95

In witness whereof, I have hereunto signed my name.

ISRAEL PERPER.
